UNITED STATES PATENT OFFICE.

JULIUS A. DYBLIE, OF JOLIET, ILLINOIS.

CLEANING-DOOR FOR HOT-BLAST STOVES.

1,210,436.

Specification of Letters Patent. Patented Jan. 2, 1917.

Application filed December 8, 1915. Serial No. 65,707.

To all whom it may concern:

Be it known that I, JULIUS A. DYBLIE, a citizen of the United States, residing at Joliet, in the county of Will and State of Illinois, have invented certain new and useful Improvements in Cleaning-Doors for Hot-Blast Stoves, of which the following is a specification.

My invention relates to hot blast stoves, and has particular reference to a novel mounting of the door which closes the cleaning openings in said stove. These doors are commonly mounted for sliding movement across the openings, being hung on rollers which engage a track secured to the walls of the stove, or to the door frame. In order to make a blast-tight joint in the door and in the frame, it is common to provide a packing material, such as asbestos, at the point of engagement between the door and frame, this packing being dovetailed into an annular groove in the door and adapted to project beyond the face of the door. In rolling the door to cover the opening, the asbestos packing is frequently bruised and destroyed by contacting the frame.

An object in my invention is, therefore, to provide means whereby the door in its movement transversely of the opening shall be caused to move away from the frame immediately at the beginning of its sliding movement.

The invention will be more readily understood by reference to the accompanying drawings, wherein—

Figure 1 is an elevation of a fragment of a hot blast stove to which my improvement has been applied; Fig. 2 is a plan view of the same; Fig. 3 is an elevation taken at right angles to that of Fig. 1; and Fig. 4 is an enlarged sectional view showing a fragment of the lower portion of the door and frame.

In the drawings, the stove is indicated at 10, the opening into which is bounded by a tubular flanged portion 11. Secured to this tubular portion through the medium of the outer flange 12, is a door frame 13. A door 14 is provided as a closure for the opening through the frame, this door being of circular form in the present instance and being mounted for sliding movement across

the opening by means of a bracket 15, a trolley 16 and a track 17. Mounted on the lower portion of the door 14 is the bracket 19, which, in the present instance, carries a spindle 20, on which an anti-friction roll 21 is mounted. This roll is adapted to contact a guide strip 22, supported on suitable brackets 23 secured to the door frame, the guiding member being provided with a laterally deflected portion 24. As will be seen in Fig. 4, the inner edge of the annular door is provided with a packing material 25, such as asbestos, which is dovetailed or set into the face of the door.

Due to the position of the deflected portions of the track and guide, a movement of the door to the right, as viewed in Fig. 1, will result in the door being swung away from the door frame, whereupon it may be slid transversely as desired, without danger of injuring the packing material.

It will be understood, of course, that the form and arrangement of the door and opening may be changed to suit different conditions, and I consider such modifications within the spirit of my invention.

I claim:

1. In a device of the class described, the combination of a furnace wall having an opening therein, a frame bounding said opening, a straight track mounted above said opening, a track mounted below said opening, said latter track having a curved or deflected portion, a door mounted for sliding movement on said straight track, said door having a projection engaging said curved track, said latter track being so located as to positively retain said door in an inclined position when out of register with said opening, and packing material carried by said door and adapted to seal the same in its position over said opening, substantially as described.

2. In a hot blast stove, the combination of a wall providing an opening, a track mounted above said opening, a door adapted to be slid on said track and mounted for limited swinging movement from the bottom of said door outwardly, a track mounted below said opening and being provided with a laterally deflected portion for cooperation with said door to cause the same to swing away from

said wall, and packing material carried by
said door, the arrangement being such that
as the door is moved in front of said open-
ing it is permitted to swing on its point of
5 support and bring the packing material
into engagement with the wall surrounding
said opening, substantially as described.

Signed at Joliet, Ill., this 29th day of
Nov., 1915.

JULIUS A. DYBLIE
